UNITED STATES PATENT OFFICE.

JACOB F. KOHLER, OF NEW YORK, N. Y., ASSIGNOR TO METAL LAMP CORPORATION, A CORPORATION OF NEW YORK.

DESIGN FOR A COMBINED LAMP SHADE AND STAND.

Application filed January 15, 1923. Serial No. 4,885. Term of patent 3½ years.

To all whom it may concern:

Be it known that I, JACOB F. KOHLER, a citizen of the United States, residing in the city, county, and State of New York, and doing business at 8720 Sixteenth Avenue, Brooklyn, New York, have invented a new, original, and ornamental Design for Combined Lamp Shade and Stand, of which the following is a specification, reference being had to the accompanying drawing, forming part thereof.

The figure is a view of the combined lamp shade and stand in front elevation.

I claim:

The ornamental design for a combined lamp shade and stand as shown.

JACOB F. KOHLER. [L. S.]
